UNITED STATES PATENT OFFICE.

ADOLF RITTERSHAUSSEN, OF CASSEL, GERMANY.

THERMO-ELECTRIC FILE.

No. 911,446.

Specification of Letters Patent.

Patented Feb. 2, 1909.

Application filed June 9, 1908. Serial No. 437,591.

To all whom it may concern:

Be it known that I, ADOLF RITTERSHAUSSEN, subject of the Emperor of Germany, residing at Cassel, in the Empire of Germany, have invented certain new and useful Improvements in Thermo - Electric Piles, of which the following is a specification.

There are known thermo-electric piles, in which the heating and cooling surfaces are 10 annular and concentric, so that a hollow cylinder is formed, the inside of which shows exclusively heating surfaces and the outside exclusively cooling surfaces. Such thermo-electric piles are, however, uneconomic, 15 since considerable losses are produced, as neither the ohmic loss (that is the loss produced by the conductivity resistance) nor the transmission of heat through the internal parts has been taken into consideration.

20 My invention relates to improvements in such thermo-electric piles, whereby their useful effect is considerably increased. The metallic components of each couple consist each of two concentric rings which are quite distinct and are connected together only by narrow or thin parts, the cross section of which depends upon the required stability and the current to be conducted through them. The several components are not connected with 25 one another on their contact faces by soldering as usual, but they are combined in a special new manner. The thermo-electric pile so constructed is most advantageous, as all excessive ohmic and caloric losses are 30 avoided. The new construction also renders it possible to improve upon the manner of heating the pile for obtaining a considerable saving in heat.

I will now proceed to describe my invention with reference to the accompanying drawing, in which—

Figure 1 is a vertical longitudinal section through a thermo-electric pile embodying my invention. Fig. 2 is a horizontal cross section through the same, Fig. 3 shows on an enlarged scale a vertical radial section through the right half of a modified pile proper, and Fig. 4 shows diagrammatically a modification of the heating device.

50 Similar letters of reference refer to similar parts throughout the several views.

The thermo-electric pile shown at Fig. 1 comprises a series of superposed couples each formed of two metallic components. Each

component of the one electrically active 55 metal consists of an internal ring *a* and an external ring *b*, which are connected together by means of several thin horizontal arms *e*, as is clearly shown at Figs. 2 and 3. The two rings *a* and *b* are on the inside 60 and outside respectively of the pile proper. Each component of the other electrically active metal consists of an internal ring *c* and an external ring *d*, which are connected together by means of several thin radial vertical arms *f* as is shown. The cross section of the arms *f* and *e* is made only so large as is required by the stability of the pile proper and by the electric current to be transmitted through them, the ohmic and caloric losses 65 being at the same time taken into consideration, they depending upon the desired maximum useful effect of the pile. The latter is obviously obtained when the loss of heat in the transmission through the arms *e* and *f* 70 plus the ohmic loss is made a minimum. The contact surface *h* between the proximate internal rings *a* and *c* of any two components is in the drawing assumed to be the electrically active heating surface, and the contact 75 surface *k* between the proximate external rings *d* and *b* of any two components is assumed to be the electrically active cooling surface. Preferably these two surfaces are 80 made alike, that is to say, the product of the periphery and of the height should be the same for the heating surface as well as for the cooling surface. In order to avoid other losses of heat in the arms *e* and *f* and also to 85 prevent the direct radiation of heat from the heating surface *h* to the cooling surface *k* a bad heat-conductor *g* of any known kind is 90 preferably inserted between the internal rings *a* *c* and the external rings *d* *b* and is 95 made to fill up the space, see Fig. 1.

With the construction just described of the thermo-electric pile the resulting contact surface at the heating surface *h* as well as at the cooling surface *k* will be very large, so that the resistance of the contact and thereby the ohmic loss will be reduced. The losses caused by the transmission of heat through the arms *e* and *f* and by the direct radiation of heat from the heating surface *h* to the cooling surface *k* are also reduced to a 100 minimum. Further all other surfaces, to which any undesirable heat might be supplied or from which this heat might be car-

ried off, are avoided. The said contact surfaces are according to my invention still further increased by providing the proximate rings with projections and recesses or 5 grooves adapted to engage each other, so that in this manner within the same height a considerably greater contact surface is obtained than before without at the same time increasing the other losses which are 10 proportional to the said height. In Fig. 3 the said projections and recesses or grooves are shown as formed by a fine and very deep screw-thread. The diameter and the height of the electrically active heating and cooling 15 surfaces depend upon the strength of the current passing through the couple and can therefore be determined from the beginning. In Fig. 1 the diameter of the cooling surface k is double that of the heating surface h and 20 therefore the height of the former is made only half that of the latter. Owing to the horizontal arms e the total effective heating surface of each couple exposed to the action 25 of the heating gases is of course larger than the electrically active heating surface h , its height H being like the sum of the height H_a of the heating surface h plus the height of the arms e , see Fig. 3. Of the heat supplied 30 to the effective heating surface of the height H the larger part passes through the electrically active heating surface h of the height H_a , while the rest passes through the arms e outwards. In the electrically active heating 35 surface h of the height H_a the heat is turned into electricity, when a drop of the temperature will take place in accordance with the theory of the conversion of heat into work.

I make the height of the external rings b 40 on the outside of the pile about like that of the internal rings a on the inside of the pile, and consequently I make the height of each external ring b larger than that K_a of the cooling surface k , viz. like the sum $K_a + K_s$, 45 see Fig. 3. I connect the upper part of the height K_s in about its middle with the several arms e . Then the heat passing through the arms e and forming a source of loss for the couple is distributed over the cooling 50 surface of the height K_s , which adjoins the effective cooling surface of the height K_a , so that the said heat can be at once carried off by cooling the said surface of the height K_s and is prevented from exercising any injurious influence upon the electrically active 55 cooling surface k by heating the same.

If for practical reasons not all the heat passing through the heating surface of the height H_a can be turned into electricity, the 60 rest of the same will pass through the arms f and will be increased by the heat produced by the Joule and Peltier effects, so that this sum of heat will require to be carried off from the effective cooling surface of the 65 height K_a . The proportion, in which the

heights K_a and K_s stand, is determined by the ratio of the heat units to be carried off from the two cooling surfaces.

The cooling by air being objectionable, since the space at disposal is too restricted, 70 I prefer to cool the outside of the pile with water. For this purpose I dispose the thermo-electric pile so far described within the central tubular wall t of a cooling vessel C , which may be of any known and approved 75 construction. This vessel C may be closed at the top, as shown, or it may be left open, and the cooling water may be passed through it in any known manner. For example the cold water may enter the vessel C at its 80 bottom through a tube o and circulate around the internal wall t while rising upwards, whereupon the warm water may leave the vessel C at its top through a tube p . The internal tubular wall t is preferably 85 made thin and is insulated from the outside of the pile proper, preferably by means of a thin layer of insulating material, such as for example lacquer or the like. As the 90 cooling surface of the height K_a , which depends upon the strength of the current, forms only a part of the total cooling surface, as described above, the advantage is obtained, that the amount of heat to be carried off per unit of cooling surface is exceeding 95 small and very much less than that which as a rule is considered permissible in technical apparatus.

With the known thermo-electric couples the components are combined either by 100 soldering the different metals on one another or by casting one metal around the other one. The latter method can be employed only in special cases, while the former method is in general use, but it presents the 105 following defect: There would be a layer of soldering material between the two different metals, so that the electric current will necessarily have to pass through two contact surfaces, whereby of course the contact 110 resistance is doubled. It would not do to connect the two metals by simply applying them to one another, for example by screwing one metal into the other metal or by any other similar method, since the contact 115 could not be made sufficiently intimate. It would then be impossible to procure an exact fit on all places between the two metals, as it should be for keeping as low as possible the resistances of the transmission. According 120 to my invention the two metals are connected together by any suitable means but preferably by methods which produce a most intimate combination of the two metals without any noticeable space. It is only 125 with the aid of such a method that the increase of the contact surfaces can be utilized. When taking into consideration, that the resistance of transmission between the components of a thermo-electric couple forms 130

an essential source of losses, it being inversely proportional to the size of the contact surface, it will be clear, that according to my invention this loss can be quite considerably reduced.

When employing the electrolysis, one of any two proximate rings of the several components may be formed by electrolysis and the several rings in the pile may be produced 10 by the electrolysis in any convenient order and may be connected with one another by means of the arms. It is obvious to any one versed in the art, in what manner the electrolysis may be employed for constructing the thermo-electric pile. When employing 15 pressure, the external rings intended to surround internal rings may be heated and applied to the latter, after which they are allowed to contract by cooling off. Or they 20 may be forced on the internal rings by hydraulic pressure. Any other known method may also be employed for obtaining similar effects.

The lowermost couple of the pile described is provided with a terminal q of any known construction, and the uppermost couple with another terminal r . The cylindrical cavity of the pile is preferably closed with a suitable bottom s below and a cover 25 n (indicated by dotted lines in Fig. 1) above, both parts being made from any inactive material. A heating pipe i is fastened in the bottom s and is provided with several holes l in its internal tapering and closed end. A 30 small hole m is provided in the cover n . This closing of the cavity of the pile in combination with the large contact surface of the heating surfaces h permits it to heat the new thermo-electric pile in a special and 35 economical manner, as will be hereinafter described.

With the known thermo-electric piles it is absolutely necessary to use a far greater quantity of cold air than is necessary for the 40 combustion, in order to reduce the temperature of combustion, so as to prevent the components having a low melting point from melting. In opposition to this manner of heating I employ the spent gases for 45 heating the pile, since these gases possess a comparatively low temperature and I burn only a small quantity of fresh combustible mixture which is sufficient for reheating the spent gases, so as to utilize their heat to the 50 utmost for heating the pile. The combustible mixture passing through the heating pipe i and entering the nearly completely closed chamber A through the holes l is 55 lighted and burns. The combustion is sufficient for reheating the spent gases filling up the chamber A , in other words it replaces the heat given off by the spent gases to the 60 heating surfaces of the pile. Only an excess of the spent gases corresponding to the 65 quantity of gases produced during the com-

bustion of the fresh combustible mixture is permitted to escape from the chamber A through the hole m of the cover n . The area of the holes l in the tapering end of the heating pipe i is determined by the quantity 70 of combustible mixture which is required for reheating the spent gases up to the desired temperature. Thus the temperature of the fresh burned gases produced during the combustion is reduced by the spent gases 75 and not by an excess of cold air as hitherto. Obviously a great saving in combustible mixture is thereby gained.

Where so preferred, the spent gases may be utilized in the manner diagrammatically 80 illustrated at Fig. 4. That is to say, the internal diameter of the effective heating surfaces of the several superposed couples of the pile is gradually and successively increased from below upwards, and between 85 the several couples separate partitions $n^1, n^2, \dots$ with heating pipes $i^1, i^2, \dots$ are inserted. Then the combustible mixture escaping from the holes l of the lowermost pipe i will during its combustion reheat the spent 90 gases in the chamber within the lowermost couple for heating the heating surface of the latter, whereupon the spent gases passing upwards through the hole m^1 in the first partition n^1 will be reheated by the 95 combustion of the combustible mixture escaping from the holes l of the second heating pipe i^1 . Of course the volume of the spent gases will be thereby increased and for this reason the chamber is made larger in 100 diameter. After heating the heating surface of the second couple the spent gases pass upwards through the hole m^2 in the second partition n^2 to be reheated by the 105 combustion of the combustible mixture escaping from the holes l of the third heating pipe i^2 , and so on. Of course the areas of the holes $l, l^1, l^2, \dots$ of the several heating tubes $i, i^1, i^2, \dots$ will be determined by the 110 heat units which are required for reheating the spent gases in the several chambers.

The thermo-electric pile described may be varied in many respects without departing from the spirit of my invention.

I claim:

1. A thermo-electric pile comprising a plurality of superposed annular couples, each couple formed of two components of different metals and each component consisting of two concentric cylindrical rings and arms between them, the rings of the components of one active metal being in intimate contact with the proximate rings of the components of another active metal and the product of the periphery and of the height of each contact surface in the proximate rings being substantially uniform throughout the pile.

2. A thermo-electric pile comprising a plurality of superposed annular couples, each couple formed of two components of differ-

115

120

125

130

ent metals and each component consisting of two concentric cylindrical rings and arms between them, the rings of each component of one active metal being approximately in 5 the same plane and in intimate contact with the proximate rings of two neighboring components of another active metal, the product of the periphery and of the height of each contact surface in the proximate rings 10 being substantially uniform throughout the pile.

3. A thermo-electric pile comprising a plurality of superposed annular couples, each couple formed of two components of 15 different metals and each component consisting of two concentric cylindrical rings and arms between them, the internal ring of each component of one metal inclosing the internal ring of the next component of 20 another metal, while the external ring of the former is inclosed by the external ring of the other next component of another metal, all the proximate rings being in intimate contact with one another and the product of the 25 periphery and of the height of each contact surface being substantially uniform throughout the pile.

4. In a thermo-electric pile, the combination with a plurality of superposed annular 30 couples, each couple formed of two components of different metals and each component consisting of two concentric cylindrical rings and arms between them, the internal ring of each component of one metal 35 inclosing the internal ring of the next component of another metal, while the external ring of the former is inclosed by the external ring of the other next component of another metal, all the proximate rings being in intimate 40 contact with one another and the product of the periphery and of the height of each contact surface being substantially uniform throughout the pile, means for producing a relative difference of temperature 45 between the outside and the inside of the pile.

5. In a thermo-electric pile, the combination with a plurality of superposed annular couples, each couple formed of two components of different metals and each component 50 consisting of two concentric cylindrical rings and arms between them, the internal ring of each component of one metal inclosing the internal ring of the next component of another metal, while the external ring of the 55 former is inclosed by the external ring of the other next component of another metal, all the proximate rings being in intimate contact with one another and the product of the periphery and of the height of each 60 contact surface being substantially uniform throughout the pile, while the rings on the inside and outside of the pile respectively have the same height and are arranged to provide a narrow space between adjacent 65 superposed couples, means for producing a

relative difference of temperature between the outside and the inside of the pile.

6. A thermo-electric pile comprising a plurality of superposed couples, each couple formed of two components of different metals, and each component consisting of two concentric cylindrical rings and arms between them, the rings of the components of one active metal being in intimate contact with the proximate ring of the other active 75 metal.

7. A thermo-electric pile comprising a plurality of superposed couples, each couple formed of two components of different metals and each component consisting of two concentric cylindrical rings and arms between them, the rings of the components of one active metal being in intimate contact with the proximate ring of the other active metal, the proximate faces of the respective parts being provided with projections and recesses to inter-engage one another for increasing the contact surface.

8. In a thermo-electric pile, the combination with a plurality of superposed annular couples, each couple formed of two components of different metals and each component consisting of two concentric cylindrical rings and arms between them, the rings of the components of one active metal being in intimate contact with the proximate rings of the components of another active metal and the product of the periphery and of the height of each contact surface in the proximate rings being substantially uniform throughout the pile, of a bad heat-conductor filling up the internal annular spaces in the superposed couples, a heating pipe for combustible mixture, a bottom of thermo-electrically inactive material closing the central cavity of the lowermost couple and surrounding the end of said heating pipe, a cover of thermo-electrically inactive material with a hole for closing the central cavity of the uppermost couple whereby a heating chamber is formed for containing the spent gases and permitting their heat to be utilized, and a cooling vessel surrounding said superposed couples and insulated therefrom.

9. In a thermo-electric pile, the combination with a plurality of superposed annular couples, each couple formed of two components of different metals and each component consisting of two concentric cylindrical rings and arms between them, the rings of each component of one active metal being approximately in the same plane and in intimate contact with the proximate rings of two neighboring components of another active metal, the product of the periphery and of the height of each contact surface in the proximate rings being substantially uniform throughout the pile, of a bad heat-conductor filling up the internal annular spaces in the superposed couples, a heating pipe for 115 120 125 130

combustible mixture, a bottom of thermo-electrically inactive material closing the central cavity of the lowermost couple and surrounding the end of said heating pipe, a cover of thermo-electrically inactive material with a hole for closing the central cavity of the uppermost couple whereby a heating chamber is formed for containing the spent gases and permitting their heat to be utilized, and a cooling vessel surrounding the pile and insulated therefrom.

10. In a thermo-electric pile, the combination with a plurality of superposed annular couples, each couple formed of two components of different metals and each component consisting of two concentric cylindrical rings and arms between them, the internal ring of each component of one metal inclosing the internal ring of the next component of another metal, while the external ring of the former is inclosed by the external ring of the other next component of another metal, all the proximate rings being in intimate contact with one another and the product of the periphery and of the height of each contact surface being substantially uniform throughout the pile, of a bad heat-conductor, filling up the internal annular spaces in the superposed couples, a heating pipe for combustible mixture, a bottom of thermo-electrically inactive material closing the central cavity of the lowermost couple and surrounding the end of said heating pipe, a cover of thermo-electrically inactive material with a hole for closing the central cavity of the uppermost couple, whereby a heating chamber is formed for containing the spent gases and permitting their heat to be utilized, and a cooling vessel surrounding the pile and insulated therefrom.

11. In a thermo-electric pile, the combination with a plurality of superposed annular couples, each couple formed of two components of different metals and each component consisting of two concentric cylindrical rings and arms between them, the internal ring of each component of one metal inclosing the internal ring of the next component of another metal, while the external ring of the former is inclosed by the external ring of the other next component of another metal, all the proximate rings being in intimate contact with one another and the product of the periphery and of the height of each contact surface being substantially uniform throughout the pile, while the rings on the inside and outside of the pile have the same height and are arranged to provide a narrow space between adjacent superposed couples, of a bad heat-conductor filling up the internal annular spaces in the superposed couples, a heating pipe for combustible mixture, a bottom of thermo-electrically inactive material closing the central cavity of the lowermost couple and surrounding the end of said heating pipe, a cover of thermo-electrically inactive material with a hole for closing the central cavity of the uppermost couple, whereby a heating chamber is formed for containing the spent gases and permitting their heat to be utilized, and a cooling vessel surrounding the pile and insulated therefrom.

In testimony whereof I have signed my name to this specification in the presence of two subscribing witnesses.
